UNITED STATES PATENT OFFICE.

BENEDIKT RÜTTI, OF BALSTHAL, SWITZERLAND.

LOCKING DEVICE FOR DOUBLE FRENCH GLAZED WINDOWS AND DOORS.

1,119,194.

Specification of Letters Patent.

Patented Dec. 1, 1914.

Application filed April 11, 1913. Serial No. 760,529.

To all whom it may concern:

Be it known that I, BENEDIKT RÜTTI, a citizen of Switzerland, and resident of Balsthal, a small place in the Canton of Solothurn, Switzerland, have invented a Locking Device for Double French Glazed Windows and Doors, of which the following is a specification.

This invention has reference to certain new and useful improvements in locking devices particularly adapted for use with double glazed windows and doors. In hitherto known windows and doors of this kind the two frames carrying the glazing of one and the same window are usually attached to one another by means of screws or the like, so that for the purpose of cleaning the inner faces of the glazings the screws had to be detached to render the said glazings accessible. This naturally involved considerable time and labor.

It is the object of the present invention to obviate these drawbacks, a locking device, hereinafter described, being provided which allows of the locking and opening respectively of the two adjacent frames of double glazed windows.

The accompanying drawing shows the application of the locking device on a French window.

In this drawing: Figure 1 shows a front elevation of the complete mechanism; Fig. 2 shows a side elevation thereof; Fig. 3 shows a section through line A—B, Fig. 1; Fig. 4 shows a vertical section through line C—D of Fig. 5, the two frames of the common window being in disengaged position, a detail also being illustrated in section; Fig. 5 shows a view similar to that illustrated in Fig. 1.

a and b designate the two windows, each window comprising two frames 1 and 2 and 3 and 4 respectively, and each of the frames having a glazing mounted therein in the usual manner. The frame 1 has a groove within which a vertical rod 5 is adapted to slide, the lower end of the said rod engaging, when the corresponding window is closed, in a sleeve or a bridge of known construction provided and arranged below the lower end of the windows, thereby keeping the two windows closed. Pivoted to the frame 1 at the point designated by 6 is a U-shaped handle 7 both ends thereof being fashioned into

plates 8. One of these plates 8 is adapted to engage, when the windows are closed, with a hook 9 mounted on the frame 3 of the window b, and the other plate lies partially in a recess provided in the rabbet-ledge of the frame 1. This latter plate is connected with the vertical rod 5 by means of an arm 10 integral with this rod, the said arm 10 being devised so that it can play in a suitable opening provided in the frame 1.

The object of the handle 7 is to permit of the vertical movement of the rod 5 which, at a certain distance from each other, has two integral projections 11 (Fig. 4) each of the latter moreover being provided with a transversely disposed head 12. Provision is made immediately opposite the said projections 11 of plates 13 mounted in suitable recesses of the frame 2, these plates having longitudinal slots 14 terminating in square openings 15. The latter allows of the disengagement of the corresponding projections 11 with head 12 from the recesses in the frame 2 when the two frames are to be disconnected. On the other hand if these frames are to be attached to one another the rod 5, subsequent to the insertion of the projections 11 into the square openings 15, is moved upward so that the heads 12 of the projections 11 engage within the slot 14 of the plates 13.

When the windows are closed the handle 7 is in the position according to Fig. 1, and the projections 11, 12 are engaging within the openings 15 of the plates 13. Assuming that the handle 7 is now turned upwardly, the rod 5 is also moved in an upward direction, its lower end thereby being withdrawn from the locking sleeve or bridge and allowing of the opening of the window a. Simultaneously with the movement of the handle 7 the projections 11 are moved behind the narrow slot 14 of the plates 13 so that the frames 1 and 2 are still fastened to each other. When the opening of the window a has taken place the handle 7 may be moved into the position shown in full lines in Fig. 5 thus causing a downward movement of the rod 5 and bringing the projections 11 opposite the openings 15. In this position projections 11 may be disengaged, that is the frame 2 may be swung outward thereby allowing an easy access to the glazings of both frames.

In order that the frames 3 and 4 may also be detached from each other, provision is made within the frame 4 of the window *b* of a vertical groove within which a rod 20 is adapted to slide (Figs. 2 and 3). At a suitable distance from each other are two hooks 21 integral with the said rod 20 which normally, that is in closed position of the frames, project into a recess in the frame 4 and engage with plates 22 bridging said groove. The rod 20 is furthermore pivoted at its lower end 23 to a double armed adjusting lever 24 which in turn is pivoted to a bolt 25 the latter being journaled in a plate 26 mounted on the frame 3. When the window *b* is disengaged from window *a*, the aforesaid adjusting lever 24 is adapted to be swung from its vertical position, Fig. 1 into a horizontal position, thereby moving the rod 20 in a downward direction and causing the hooks 21 to lie below the plates 22. In this position the frames 3 and 4 may easily be detached from each other and in this also, the glazings of both frames are accessible.

Having now fully described my said in-

vention what I claim and desire to secure by Letters Patent is:—

In a locking device for double glazed French windows, the combination of a pair of frames and a frame adapted to engage therewith, a U-shaped handle pivoted to one of the frames, said handle having a plate apertured to receive a pin, the said plate being movable with the handle, a rod having a pin entering the slot of the plate, members 35 on the rod adapted to interlock with the other frame of the pair, a plate on the frame with which the first mentioned pair of frames coacts, an engaging device on the said last mentioned plate, and a member on 40 the U-shaped handle adapted to interlock with the engaging device.

In testimony whereof I have hereunto set my hand in the presence of two subscribing witnesses.

BENEDIKT RÜTTI.
